UNITED STATES PATENT OFFICE.

GEORGE H. CHAPMAN, OF CHICAGO, ILLINOIS.

ELECTRIC SWITCH.

Application filed March 16, 1922. Serial No. 544,129.

To all whom it may concern:

Be it known that I, GEORGE H. CHAPMAN, a citizen of the United States, residing at Chicago, in the county of Cook and State of Illinois, have invented certain new and useful Improvements in Electric Switches, of which the following is a specification.

This invention relates to an electric switch more especially designed for recording stop combinations on organs, but capable of use as a circuit controlling switch in other relations.

Among the leading objects of the invention are, to provide a switch of the rotary type which will avoid any twisting or turning movement of the circuit wire which is permanently connected to the switch, thus avoiding breaking of the wire through repeated bending; to provide a switch of the 20 rotary type capable of turning between two spaced contact strips or plates which will have a positive spring pressure contact with either of said strips or plates or may be turned to an intermediate or neutral position between them; to provide a switch wherein perfect electric contact will at all 25 times exist, unaffected by swelling or shrinking of the wood of the recording switch-board or variations in the length of the 30 switch stem, or thickness of the wood; to provide a type of switch permitting of grouping a plurality of switches on very close centers on the recording switch-board; and to provide a switch which cannot be 35 damaged or incapacitated by pull or tension from the front—a fault existing in most of the recorder switches now in use, in which the switch can be carelessly or accidentally lifted so high that the spring tension is destroyed.

These, and other objects and advantages of the invention, will be apparent to persons skilled in the art as the same becomes better understood by reference to the following description, taken in connection with the accompanying drawing in which I have illustrated one practical embodiment of the invention, and wherein—

Fig. 1 is a front elevation of a portion of 50 a recorder board having a group of my improved switches mounted thereon;

Fig. 2 is an enlarged rear elevation of the same;

Fig. 3 is a cross-section on the line 3—3 55 of Fig. 2;

Fig. 4 is a perspective detail of an end

portion of one of the contact strips showing an upwardly struck lug to which the circuit wire is soldered; and

Fig. 5 is a detail elevation of the switch 60 post.

Referring to the drawing, 6 designates the recorder board of a pipe organ construction, to the face of which are secured one or more pairs of flat parallel copper strips 7 and 8; 65 two such pairs being shown. Each strip, in practice, is connected to a circuit wire leading through a stop operating magnet, as hereinafter described. Between the contact strips 7 and 8 the board 6 is bored to 70 receive round switch posts 9, each of which latter has a widened and flattened upper end portion 10 forming a turning knob or handle. From the metal of the knob 10 there is cut and bent downwardly a rectangular offset finger or prong 11, the free end 75 of which is adapted, under a turning movement of the post, to make contact with either of the strips 7 and 8 or with the surface of the board between the strips. 80

On the back of the board 6 are laid a pair of circuit wires 12 and 13 leading from a source of current through stop operating magnets. These wires are passed through holes 14 in the board and soldered at their 85 respective ends to upstanding lugs or tongues 15 (Fig. 4) punched from the strips 7 and 8. On the back of the board are also laid a series of circuit wires 16 from the other side of the battery or other current 90 generator. Each of the wires 16 is connected to an integral arm 17 of a metal washer 18, which latter is also formed with a downwardly bent tooth 19 that is driven into the board, as shown in Fig. 3, and thus prevents the washer from turning on its axis. 95

The washer is centrally apertured for the passage of the post 9, and the projecting portion of said post is encircled by a compression spring 20. One end of the spring 100 20 is stepped on the washer 18 and its other end abuts against a washer 21 confined on the outer end of post 9 by a cotter-pin 22. The spring thus exerts a thrust on the post 9 which is resisted only by the contact 105 finger 11, thus insuring a perfect electric contact with either of the strips 7 and 8, and also firmly holding the finger 11 in intermediate or neutral position in contact with the board, and thus preventing any 110 accidental closing of either circuit. The washer 18 loosely fits the post 9 in order to

reduce as much as possible the tendency of the washer to turn with the post, and the current is conducted to the post through the spring 20, abutment washer 21 and cotter 5 pin 22.

From the foregoing it will be apparent how the described structure effectuates the stated purposes or objects of the invention. Since the post 9 can turn freely in the washer 18, and the latter is locked to the board against turning, the arm 17 is always stationary and there can be no twisting or turning of the circuit wire 16, which, in other constructions moves, and often breaks 15 at this point. The action of the spring 20 always causes the finger 11 to have a positive spring pressure contact with either of the strips, or with the surface of the board between the strips; and this contact is manifestly unaffected by swelling or shrinking of the wood of the recording switch-board or mechanical variation in length of the switch post. The narrow structure of the switches also permits the grouping of a plurality of 25 switches on very close centers on the board. Finally, no matter how hard or far the post may be pulled out when operating the switch, the spring 20 cannot be permanently strained, and always reacts to give the 30 positive pressure contact described. Moreover, by forming the contact finger or prong 11 from the stock of the knob or handle 10, simplicity of structure and economy of material are secured.

Although I have shown and described my invention as embodied in a recorder switch for organs, and contemplate that such will be its principal use, it is manifest that the principle of the invention may find embodiment in circuit controlling switches for other purposes and in other relations. Hence the invention is not limited to a recorder switch, nor to the precise details of structure and arrangement shown, but may be modified 45 and varied within the purview and scope of the appended claims.

I claim—

1. In a rotary electric switch, the combination of a switch-board, a switch post rotatably mounted in said board, a fixed contact member on a surface of said board at one side of said switch post, an operating knob on one end of said post, a contact finger cut and bent outwardly from said knob, and a spring forcing said post endwise in a direction to press said finger against said contact member.

2. In a rotary electric switch, the combination of a switchboard, a switch post rotatably mounted in said board, a washer encircling said post and formed with a prong

driven into said board and with a radially extended arm for connection to a circuit wire, and a compression spring interposed between said washer and one end of said post, said washer, spring and post constituting current-conducting elements of the switch.

3. In a rotary electric switch, the combination of a switchboard, a switch post rotatably mounted in said board and carrying a spring abutment on its projecting end, a flat washer encircling said post and formed with a prong driven into said board, and, opposite said prong, with a radial outwardly inclined arm for connection to a circuit wire, and a coil compression spring encircling said post between said washer and said abutment; said washer, spring, spring abutment and post constituting current-conducting elements of the switch.

4. In an electric switch of the character described, the combination of a switchboard, a metal switch post rotatably mounted in and projecting in rear of said board, a fixed contact member on and flush with the front surface of said board at one side of said post, a laterally extending contact finger carried by said post and movable into and out of contact with said fixed contact member under a turning movement of said post, a washer encircling said post on the rear side of said board and anchored against turning to said board, a circuit wire electrically connected to said washer, and a thrust spring between and in current-conducting relation to said washer and the projecting end of said post.

5. In an electric switch of the character described, the combination of a switchboard, a metal switch post rotatably mounted in and projecting in rear of said board, a pair of fixed contact members on and flush with the front surface of said board at opposite sides of, and equidistant from, said post, respectively, a laterally extending inwardly bent contact finger carried by said post, a flat washer encircling said post on the rear side of said board and anchored against turning to said board, an outwardly inclined radial arm on said washer, a circuit wire electrically connected to said arm, and a coil compression spring encircling said post between, and in current-conducting relation to, said washer and the projecting end of said post.

6. In a rotary electric switch, a round switch post having an integral widened and flattened knob formed as a longitudinal extension thereof, and a contact finger cut and bent outwardly from said knob.

GEORGE H. CHAPMAN,
